(57) **CLAIM**

The ornamental design for a condenser exhaust hood, as shown and described.

DESCRIPTION

FIG. 1 is a bottom front perspective view of the condenser exhaust hood, showing the new design;

FIG. 2 is a bottom rear perspective view thereof;

FIG. 3 is a front elevational view thereof;

FIG. 4 is a rear elevational view thereof;

FIG. 5 is a side elevational view thereof;

FIG. 6 is another side elevational view thereof;

FIG. 7 is a top plan view thereof;

FIG. 8 is a bottom plan view thereof; and,

FIG. 9 is a top front perspective view thereof.

The broken lines are included for the purpose of illustrating unclaimed portions of the condenser exhaust hood and form no part of the claimed design.
